UNITED STATES PATENT OFFICE.

THEOPHILOUS L. BEAR, OF CAMDEN, NEW JERSEY.

WATCH-CASE SPRING.

SPECIFICATION forming part of Letters Patent No. 311,563, dated February 3, 1885.

Application filed February 14, 1884. (No model.)

To all whom it may concern:

Be it known that I, THEOPHILOUS L. BEAR, a citizen of the United States, and a resident of the city of Camden, State of New Jersey, have 5 invented a new and useful Improvement in Watch-Case Springs, of which the following is a specification.

In the accompanying drawings, Figure 1 represents a cross-section of the case, showing the 10 spring in position. Fig. 2 is a vertical view, the spring being indicated by dotted lines. Fig. 3 is a cross-section of the rim of case at the point indicated by the line 1 2, Fig. 2. Fig. 4 is a vertical view of spring, and Fig. 5 is a 15 side view.

The device consists of a spring which is capable of being readily fitted to a case of any shape, and when in place admits of being adjusted. This is accomplished by two adjusting-screws passing vertically through the body 20 of the spring. These screws are shown at A A in Fig. 1. In fitting they are filed so that the spring can be pushed in just far enough to receive the clamping-screw B. Their ends will 25 then rest above and below on the case, as shown in Fig. 3. The effect of turning either one of the screws A will be to change the plane of the spring relatively to that of the case. They are turned by means of pliers grasping them between 30 the spring and the case. By this ar-

rangement it is possible to raise or lower the end of the spring, which is not the case, to my knowledge, with any known device. One great advantage is, that hammering the spring will be avoided, that being the present method 35 of accomplishing the vertical adjustment, often resulting in breaking the spring or rendering it more liable to break. An additional advantage is, that in the event of the screw B becoming rusted, pliers can be introduced between the rim of the case and the spring; or, by turning the screws A A, the screw B may be made to project above the rim of the case, thus permitting a firmer hold to be obtained than by a screw-driver. 40

The device is applicable to either the catch or raising-spring.

I claim—

1. The combination, in a watch-case spring, of a screw or screws passing vertically through 50 the body of the spring, for the purpose of producing a vertical adjustment, substantially as set forth.

2. The combination, in a watch-case spring, of the screws A A and the screw B, substantially as set forth. 55

THEOPHILOUS L. BEAR.
